SAVINGS BANK

George C. Carlson, Chicago, Ill.

Application February 16, 1942, Serial No. 431,805

2 Claims. (Cl. 206—1.5)

This invention relates to a novelty type of coin savings bank designed primarily for use with a photographic frame or the like.

Various types of coin banks have heretofore been designed mainly for purpose of providing a simple and inexpensive structure. In the construction of smaller size banks, the question of strength or theft of coins therefrom has never been regarded as an important factor. Smaller banks are seldom constructed to serve any purpose other than that of accumulating and holding small sums of money. In certain instances, they have been designed also as a novelty item for the purpose of carrying certain desirable advertising. The amount of the space available for the advertising matter is limited however with the consequent result that this advertising matter had little if any value.

An object of this invention is to provide a savings bank of an improved construction, and of the novelty type referred to, being particularly adapted to incorporate a picture frame in combination with a coin receptacle and an improved but simple form of lock whereby access to the interior of the bank is necessary before the photograph can be removed or replaced. The device is, therefore, useful and has certain benefits in promoting and developing certain interests in, say, the photograph field or associated fields. By retaining the means for actuating the lock affording access to the interior and by compelling the owner of the bank to appear at the time the bank is opened to remove the contents, the merchant will be in a position to rely upon the owner using the savings in purchasing photographs or the like, particularly those of infants in whose behalf the banks might be given as gifts.

A further object of the invention is to provide a structure of this type that is simple, inexpensive and of few parts.

A still further object of the invention is to provide such a structure that is effective in holding the removable part in locked position, which part may be quickly operated by the proper key either in locked or unlocked position. The parts are designed to eliminate the usual expensive lock mechanism, generally of the tumbler type, which I have found is unnecessary in carrying out the intended use of the bank.

To this end, one side of the receptacle may be in the form of a picture frame that is removable but requires disconnection in order to replace the photographic print disposed therein. I propose to provide a simple form of cleat on the inside face of this removable side of the receptacle that may

be swung into engaging relation with opposite side walls within the receptacle and thereby be held against displacement, this cleat being so arranged that it may be held in this position by a second locking element having specially engageable means operable through the coin slot in the receptacle.

Other objects and advantages of the invention will be apparent from the following description when taken in connection with the accompanying drawing, which forms a part hereof.

In the drawing:

Figure 1 is a perspective view of a device embodying the present invention;

Fig. 2 is a similar view of the device but with the picture frame side removed;

Fig. 3 is a sectional view taken along line 3—3 of Fig. 4;

Fig. 4 is a transverse section taken centrally through the device;

Fig. 5 is a sectional view taken along line 5—5 of Fig. 4;

Fig. 6 is also a perspective view but from the rear face and with a portion of the wall broken away to show the locking mechanism; and

Fig. 7 is a view of the type of key that may be used.

Referring specifically to the drawing, the device comprises a coin receptacle designated generally as 1 and a picture frame likewise broadly designated as 2 but forming the removable front wall of receptacle 1. Receptacle 1 and frame 2 may be of any suitable design that is constructed of metal, wood or plastic material. Frame 2 may have the usual opening 3 and rabbet 4 to carry the glass or celluloid front 5, the picture or photograph 6 and the backing card or wall 7. Frame 2 can be formed in any desirable way but I have found it advantageous from the standpoint of simplicity and effectiveness to provide a second rabbet 8 into which fit the edges of the two side walls 9 and 10, the top wall 11 carrying the coin slot 12 and the bottom or base 13. To give the frame 2 a slightly tilted position with reference to the vertical and still not require receptacle 1 to be tilted, base 13 has the front part 14 slanted upwardly and adjacent walls cut accordingly so that the edges fitting into rabbet 8 will slant backwardly. Thus, the removable frame 2 may be fitted into place and assume the position shown in Fig. 1.

The locking mechanism for locking frame 2 in position comprises a pivotally mounted cleat 15 carried by a pivot 16 in wall 7. This type of connection may be varied. It is desirable that

the ends of cleat 15 may be swung into engagement with cooperating members 17 and 18 carried by side walls 9 and 10. These members 17 and 18 are cut oppositely with shoulders 19 and 20, respectively, which serve to limit the swinging movement of cleat 15. As shown in the drawing, cleat 15 is adapted to swing clockwise when looking at the inside face of back 1, the right-hand end 21 entering the cut-away portion of member 17 and striking against shoulder 19. The left-hand end 22 enters the cut-away portion of member 18 and strikes against shoulder 20 at the top. The position of shoulders 19 and 20 and the direction of pivotal movement of cleat 15 may be reversed, if so desired.

To prevent cleat 15 from being dislodged from its locking position, a locking pawl 25 is pivoted at 26 to back 7 of picture frame 2. This pawl 25 is adapted to be swung upwardly against cleat 15, as shown in Fig. 6, the tight engagement bindingly holding these two parts together and keeping the ends 21 and 22 of cleat 15 against shoulders 19 and 20, respectively. When pawl 25 is employed, an actuator 27 serving the purpose of a key in this device because it is used to move parts 25 and 15 into locked or unlocked position, is inserted through coin slot 12 until its hooked tip 28 engages a cooperating part on pawl 25, which, in the case of the illustration in the drawing, is a hole 29, the tip 28 being guided into hole 29 by the surface about this hole being dished as indicated at 30. It is therefore apparent that actuator 27 may be properly called a key means although it is not designed to operate the usual tumbler mechanism heretofore employed as the locking mechanism in this type of device.

As illustrated in Fig. 3, actuator 27 is inserted through coin slot 12 and the tip 28 thereof is inserted into hole 29. Pawl 25 may then be easily moved about its pivot 26 until it is swung into engagement with cleat 15 holding it in locked position, as shown in Fig. 6, or into its lower position, as shown in Fig. 3, to permit cleat 15 to move to unlocked position.

It will be understood that back 1 is secured to frame 2, say, at several points indicated at 32, so that frame 2 is held to the coin receptacle as shown when cleat 15 carried by back 1 is swung to its locking position. Whenever photograph 6 is to be changed, plate 7 is removed from frame 2. Hence, it is essential to first remove coin receptacle 1 through the use of device 27 operating the locking parts 15 and 25. It will be apparent that actuator 27 may take any suitable form according to the design provided for pawl 25. In its simplest form, this actuator is adapted to be inserted through coin slot 12, thereby further assisting in simplifying the structure as a whole

and making it possible to provide a few parts within the bank that can be quickly operated to open the bank, either to remove the contents or to change the photograph, or both.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

- 15 1. In a device of the class described, the combination of a receptacle having fixed walls and a removable wall, one of said fixed walls having a slot in proximity to said removable wall, means for locking said removable wall to said receptacle, said means including a centrally pivoted bar member and relatively fixed means engageable by the ends of said bar member, said bar member and said fixed means being disposed within said receptacle, one being carried by said removable wall and the other being carried by said receptacle, a movable member pivoted at one end to swing into engagement with and to lock said bar member in engaging relation with said fixed means to prevent removal of said removable wall from said receptacle, and a detachable tool extending through said slot and pivotally and detachably engaging said movable member at its opposite end to move said movable member into and out of said engagement with said bar member.
- 20 2. In a device of the class described, the combination of a receptacle having fixed walls and a removable wall, one of said fixed walls having a slot in proximity to said removable wall, means for locking said removable wall to said receptacle, said means including a centrally pivoted bar member and relatively fixed means engageable by the ends of said bar member, said bar member and said fixed means being disposed within said receptacle, one being carried by said removable wall and the other being carried by said receptacle, a movable member pivoted at one end to swing into engagement with and to lock said bar member in engaging relation with said fixed means to prevent removal of said removable wall from said receptacle, and a detachable tool extending through said slot and pivotally and detachably engaging said movable member at its opposite end to move said movable member into and out of said engagement with said bar member.
- 25 3. In a device of the class described, the combination of a receptacle having fixed walls and a removable wall, one of said fixed walls having a slot in proximity to said removable wall, means for locking said removable wall to said receptacle, said means including a pivoted bar member and relatively fixed means engageable by the ends of said bar member, said bar member and said fixed means being disposed within said receptacle, one being carried by said removable wall and the other being carried by said receptacle, a movable member inside said receptacle so mounted as to swing into engagement with and to lock said bar member in engaging relation with said fixed means to prevent removal of said removable wall from said receptacle, tool engaging surfaces of predetermined formation upon said movable member, and a detachable tool extending through said slot and pivotally and detachably engaging said surfaces of predetermined formation to move said movable member into and out of said engagement with said bar member.
- 30 4. In a device of the class described, the combination of a receptacle having fixed walls and a removable wall, one of said fixed walls having a slot in proximity to said removable wall, means for locking said removable wall to said receptacle, said means including a pivoted bar member and relatively fixed means engageable by the ends of said bar member, said bar member and said fixed means being disposed within said receptacle, one being carried by said removable wall and the other being carried by said receptacle, a movable member inside said receptacle so mounted as to swing into engagement with and to lock said bar member in engaging relation with said fixed means to prevent removal of said removable wall from said receptacle, tool engaging surfaces of predetermined formation upon said movable member, and a detachable tool extending through said slot and pivotally and detachably engaging said surfaces of predetermined formation to move said movable member into and out of said engagement with said bar member.
- 35 5. In a device of the class described, the combination of a receptacle having fixed walls and a removable wall, one of said fixed walls having a slot in proximity to said removable wall, means for locking said removable wall to said receptacle, said means including a pivoted bar member and relatively fixed means engageable by the ends of said bar member, said bar member and said fixed means being disposed within said receptacle, one being carried by said removable wall and the other being carried by said receptacle, a movable member inside said receptacle so mounted as to swing into engagement with and to lock said bar member in engaging relation with said fixed means to prevent removal of said removable wall from said receptacle, tool engaging surfaces of predetermined formation upon said movable member, and a detachable tool extending through said slot and pivotally and detachably engaging said surfaces of predetermined formation to move said movable member into and out of said engagement with said bar member.
- 40 6. In a device of the class described, the combination of a receptacle having fixed walls and a removable wall, one of said fixed walls having a slot in proximity to said removable wall, means for locking said removable wall to said receptacle, said means including a pivoted bar member and relatively fixed means engageable by the ends of said bar member, said bar member and said fixed means being disposed within said receptacle, one being carried by said removable wall and the other being carried by said receptacle, a movable member inside said receptacle so mounted as to swing into engagement with and to lock said bar member in engaging relation with said fixed means to prevent removal of said removable wall from said receptacle, tool engaging surfaces of predetermined formation upon said movable member, and a detachable tool extending through said slot and pivotally and detachably engaging said surfaces of predetermined formation to move said movable member into and out of said engagement with said bar member.
- 45 7. In a device of the class described, the combination of a receptacle having fixed walls and a removable wall, one of said fixed walls having a slot in proximity to said removable wall, means for locking said removable wall to said receptacle, said means including a pivoted bar member and relatively fixed means engageable by the ends of said bar member, said bar member and said fixed means being disposed within said receptacle, one being carried by said removable wall and the other being carried by said receptacle, a movable member inside said receptacle so mounted as to swing into engagement with and to lock said bar member in engaging relation with said fixed means to prevent removal of said removable wall from said receptacle, tool engaging surfaces of predetermined formation upon said movable member, and a detachable tool extending through said slot and pivotally and detachably engaging said surfaces of predetermined formation to move said movable member into and out of said engagement with said bar member.
- 50 8. In a device of the class described, the combination of a receptacle having fixed walls and a removable wall, one of said fixed walls having a slot in proximity to said removable wall, means for locking said removable wall to said receptacle, said means including a pivoted bar member and relatively fixed means engageable by the ends of said bar member, said bar member and said fixed means being disposed within said receptacle, one being carried by said removable wall and the other being carried by said receptacle, a movable member inside said receptacle so mounted as to swing into engagement with and to lock said bar member in engaging relation with said fixed means to prevent removal of said removable wall from said receptacle, tool engaging surfaces of predetermined formation upon said movable member, and a detachable tool extending through said slot and pivotally and detachably engaging said surfaces of predetermined formation to move said movable member into and out of said engagement with said bar member.
- 55 9. In a device of the class described, the combination of a receptacle having fixed walls and a removable wall, one of said fixed walls having a slot in proximity to said removable wall, means for locking said removable wall to said receptacle, said means including a pivoted bar member and relatively fixed means engageable by the ends of said bar member, said bar member and said fixed means being disposed within said receptacle, one being carried by said removable wall and the other being carried by said receptacle, a movable member inside said receptacle so mounted as to swing into engagement with and to lock said bar member in engaging relation with said fixed means to prevent removal of said removable wall from said receptacle, tool engaging surfaces of predetermined formation upon said movable member, and a detachable tool extending through said slot and pivotally and detachably engaging said surfaces of predetermined formation to move said movable member into and out of said engagement with said bar member.

GEORGE C. CARLSON.
